UNITED STATES PATENT OFFICE.

MAX HENDLER, OF STAUNTON, ILLINOIS, ASSIGNOR TO DEWAR MANUFACTURING COMPANY, OF WILMINGTON, DELAWARE, A CORPORATION OF DELAWARE.

MINER'S LAMPLIGHTER.

1,274,544.

Specification of Letters Patent. Patented Aug. 6, 1918.

Application filed April 12, 1913. Serial No. 760,629.

To all whom it may concern:

Be it known that I, MAX HENDLER, a subject of the Czar of Russia, and residing at Staunton, Illinois, have invented a certain 5 new and useful Improvement in Miners' Lamplighters, of which the following is a full, clear, and exact description, such as will enable others skilled in the art to which it appertains to make and use the same, 10 reference being had to the accompanying drawings, forming part of this specification, in which—

Figure 1 is a side elevational view of a miner's lamp equipped with my improved 15 lighting device.

Fig. 2 is a front elevational view of the lamp with the lighter applied to the reflector thereof.

Fig. 3 is an enlarged horizontal sectional 20 view taken approximately on the line 3—3 of Fig. 2.

Fig. 4 is a perspective view of a combined bearing and holder made use of in my improved lighter.

25 My invention relates to a lighting device particularly intended for all forms of gas burning lamps, the principal object of my invention being, to provide a simple, inexpensive and convenient lighter which can be applied directly to the reflector of the lamp adjacent to the burner tip, and which lighting device, when operated, creates a spark which is thrown directly across the gas issuing from the burner tip, thereby igniting said gas.

30 My invention, while primarily designed for use in connection with the ordinary forms of miners' acetylene lamps, can be advantageously combined with all forms of 40 gas lamps.

To the above purpose my invention consists in certain novel features of construction and arrangement of parts hereinafter more fully described and claimed.

45 Referring by numerals to the accompanying drawings, 1 designates the body of a miner's acetylene gas lamp of the usual construction and comprising gas-generating means, not shown, said body being provided 50 with a gas outlet tube or burner tube 2 in the outer end of which is seated a perforated burner nipple 3.

The usual open faced concave reflector 4 is provided with a short, tubular member 5 which is adjustably seated on the tube 2, and

formed through this reflector adjacent to the burner tip 3 is a threaded aperture, and there being a flange or collar 6 formed integral with said reflector around this aperture. Screw-seated in this threaded aperture is the threaded rear portion of a combined holder and bearing 7, which constitutes part of a pyrophoric ignition attachment and which is in the form of a short tube, the forward end of which is bifurcated or slotted to form a pair of fingers 7^a. A small disk 8 is positioned between these fingers 7^a and is mounted for rotation on a pin 9, the ends of which are seated in said fingers 7^a. The edge of this disk 8 is serrated or provided with a series of sharp teeth. In the particular construction illustrated, this disk or spark wheel is located in a radial plane with reference to the burner tip and projects somewhat outside of the 75 plane of the reflector edge.

Screw-seated upon the projecting rear end of the holder and bearing 7 is a cap 10, and positioned therein and in the rear portion of the tubular member 7 is an expansive coil 80 spring 11. Arranged to slide freely through the forward portion of the member 7 is a short, cylindrical section of metal 12, or a combination of metals, which will readily give off sparks of fire when engaged by the 85 edge of the disk 8 as the latter is rapidly rotated.

The tubular holder is screw-seated, and therefore said holder can be readily adjusted backward or forward in the reflector 90 in order to bring the point of contact between the disk 8 and the section of spark-producing material directly opposite the forward end of the burner tip, and thus the sparks produced as the disk is rotated are 95 thrown directly across the mouth of the gas exit opening in said burner tip.

The operation of my improved device is apparent, for it is only necessary to place the thumb or finger on the serrated edge of 100 the disk 8 and to partially rotate said disk with a quick motion, and as a result, the teeth on said disk scrape across the forward end of the section of spark-producing or pyrophoric material, and as a result, sparks 105 of fire are produced which are thrown directly across the orifice in the burner tip 13, thereby igniting the gas as it issues therefrom. As the spark-producing material wears away it will feed forward under the 110

influence of the spring 11, and the tension of this spring can be regulated by a manipulation of the screw cap 10.

Moreover, it is evident that the relative position of the spark wheel with respect to the rim of the reflector is such that the lamp can be lighted by a sweep of the palm of the hand across the face of the reflector in contact with the spark wheel. Thus, when the palm of the hand is wiped across the periphery of the spark wheel, either while also engaging the reflector edge or not, the wheel will be rotated and the pyrophoric ignition attachment operated to ignite the gas issuing from the tip end of the burner tube. It is also evident that the palm of the hand may be held against the reflector edge in such manner as to close the reflector and accumulate a combustible gas mixture therein; and that the hand may then be wiped across the reflector edge to engage the wheel periphery and cause rotation thereof, thus effecting operation of the pyrophoric attachment and ignition of the accumulated gas.

The tubular member 5 carrying the reflector and the spark producing means is adjustably positioned on the tube 2 in order that the reflector may be rotated upon said tube 2 to bring the spark producing means above, below or to either side of the burner tip 3, thus making it possible to obtain the full benefit of the light from the ignited gas on the work upon which the miner is engaged; for instance, if the work is at the top of a drift or horizontal passage way, the reflector is turned so that the spark producing means is located below the burner tip or, if the miner is working close to the floor of the drift, the reflector is turned so that the spark producing means is positioned above the burner tip.

A device of my improved construction is comparatively simple, is very compact, occupies little space on the face of the reflector, and is adapted for use in connection with all gas burning lamps.

It will be readily understood that minor changes in the size, form and construction of the various parts of my improved device can be made and substituted for those herein shown and described without departing from the spirit of my invention, the scope of which is set forth in the appended claims.

55 I claim:

1. The combination with a lamp of the character described, having a reflector surrounding the burner tip of a lamp, of a tube seated in the wall of the reflector and extending rearwardly of the same, the inner end of said tube being provided with spaced ears projecting inwardly from the reflector wall, an abrasive wheel rotatably mounted between said ears, and having its axis disposed in a plane at right angles to the longitudinal

axis of the reflector, the periphery of said wheel projecting beyond the plane of the outer edge of the reflector wall, a stick of sparking material slidably mounted in the tube, a spring arranged in the tube and bearing against the sparking stick to force the same into frictional engagement with the abrasive wheel, and a cap threaded upon the end of said tube to removably retain the spring therein and adjust the tension thereof.

2. In an acetylene lamp, the combination of a body part, provided with means for generating gas, a reflector supported on the body part, a burner within the reflector for receiving the generated gas, and a pyrophoric ignition attachment comprising a spark wheel, said mechanism being so positioned with reference to the plane of the outer edge of the reflector that when the palm of the hand is wiped across said reflector edge it will engage with the periphery of the wheel to cause rotation thereof and operation of the pyrophoric ignition mechanism to ignite the gas.

3. In a gas lamp, the combination of a body part and means therein for generating gas, a concave reflector supported on the body part, a burner tip within the reflector connected with the interior of the body part to receive the generated gas, and a pyrophoric ignition attachment, said attachment comprising a spark wheel and pyrophoric material together with means for pressing said material against the wheel, said attachment being so applied that the periphery of the spark wheel is sufficiently close to the plane of the outer edge of the reflector in order that the palm of the hand when wiped across the reflector edge will engage with the wheel periphery to cause rotation of the wheel and igniting operation of the attachment.

4. In a gas lamp, the combination of a body part and means therein for generating gas, a concave reflector supported on the body part, a burner tip within the reflector connected with the interior of the body part to receive the generated gas, and a pyrophoric ignition attachment, said attachment comprising a spark wheel and pyrophoric material together with means for pressing said material against the wheel, said attachment being applied in such a manner that the wheel is in a radial plane with its periphery projecting a sufficient distance outside of the plane of the reflector edge in order that the palm of the hand may be wiped across the wheel periphery to cause rotation of the wheel.

5. In a gas lamp, the combination of a supporting body part, a concave reflector supported thereon, a burner tip within the reflector, and a pyrophoric ignition attachment comprising a spark wheel and pyropho-

ric material together with means for pressing the material against the wheel, said attachment being disposed within the reflector to hold the wheel in a radial plane and with its periphery in such relation to the plane of the outer edge of the reflector that the palm of the hand may be held against the reflector edge to close the reflector for the accumulation of gas and that the hand when wiped across the edge will engage with the wheel periphery to cause rotation thereof and operation of the pyrophoric attachment to ignite the accumulated gas.

6. A miner's acetylene lamp comprising the combination with a lamp body and an open-faced reflector mounted thereon, of a

burner tube communicating with the interior of said lamp body and projecting through said reflector, and an igniter including a spark-wheel mounted on said reflector in operative relation to the tip end of the burner tube, and so located with respect to the reflector rim that it may be operated to light the lamp by a sweep of the hand across the reflector in contact with the spark-wheel. 20

25

In testimony whereof I hereunto affix my signature in the presence of two witnesses, this 8th day of April, 1913.

MAX HENDLER.
